CLAIM

The ornamental design for a cushion insert for a tubing clamp, as shown and described.

DESCRIPTION

FIG. 1 is a front perspective view of a cushion insert for a tubing clamp shown in the non-operative position;

FIG. 2 is a front elevational view of the cushion insert of FIG. 1, the rear view being a mirror image thereof;

FIG. 3 is a top plan view of the cushion insert of FIG. 1;

FIG. 4 is a right side elevational view of the cushion insert of FIG. 1;

FIG. 5 is a left side elevational view of the cushion insert of FIG. 1;

FIG. 6 is a bottom plan view of the cushion insert of FIG. 1; and,

FIG. 7 is a left side view of the cushion insert of FIG. 1 shown in the operative position for supporting an elongated member. It will be understood that the broken lines shown in FIG. 7 depict environment only and form no part of the claimed design, i.e., the broken lines represent an elongated member in the form of a tube or pipe and portions of clamp halves surrounding the cushion.
